UNITED STATES PATENT OFFICE.

ARTHUR JAMES THOMPSON AND HERMAN R. BUMKE, OF MANISTEE, MICHIGAN.

BASKET-CLOSURE.

1,309,079.

Specification of Letters Patent. Patented July 8, 1919.

Application filed January 31, 1918. Serial No. 214,727.

To all whom it may concern:

Be it known that we, ARTHUR J. THOMPSON and HERMAN R. BUMKE, citizens of the United States, residing at Manistee, in the county of Manistee and State of Michigan, have invented certain new and useful Improvements in Basket-Closures, of which the following is a specification, reference being had to the accompanying drawings.

10 This invention relates to certain improvements in basket closures and has relation more particularly to a basket of a conventional bushel or fruit type and it is an object of the invention to provide novel and improved means whereby the basket closure will be effectively maintained in applied position irrespective of the position of the basket or pressure which may be imposed thereon.

15 20 The invention consists in the details of construction and in the combination and arrangement of the several parts of our improved basket closure whereby certain important advantages are attained and the device rendered simpler, less expensive and otherwise more convenient and advantageous for use, as will be hereinafter more fully set forth.

The novel features of our invention will 30 hereinafter be definitely claimed.

In order that our invention may be the better understood, we will now proceed to describe the same with reference to the accompanying drawings, wherein:

35 Figure 1 is a view in perspective of a basket having applied thereto fastening means constructed in accordance with an embodiment of our invention;

40 Fig. 2 is an enlarged fragmentary view partly in section and partly in elevation illustrating one of our improved fastening members or clips in initial position; and

45 Fig. 3 is a view similar to Fig. 2 with the fastening member or clip in locking engagement.

As disclosed in the accompanying drawings B denotes a basket of ordinary construction and which includes the staves 1 and the rims 2 connecting the upper or free 50 ends of the staves 1. 3 denotes conventional handles with which the cleat 4 coats in a well known manner for holding the closure member or cover C in applied position.

It often occurs in the handling of a basket of this type that the cleat 4 becomes accidentally or otherwise detached resulting in

the spilling of the contents of the baskets especially when the basket is inverted or laid on its side and rolled about. It also often occurs that the cleat 4 becomes detached 60 when excessive pressure is imposed upon the basket when in stack which has a tendency to cause the lower basket to spread.

To maintain the closure member or cover C in applied position in the event the cleat 65 4 should become detached, we employ the members or clips M preferably two in number, although we do not wish to be understood as limiting ourselves in this respect.

Each of the members or clips M comprises 70 a strand of wire of predetermined length and having one end portion returned as at 5 to afford an inwardly facing hook member adapted to straddle the lower marginal portion of the outer rim 2 between adjacent 75 staves 1.

Initially the opposite end portion of the strand of wire is bent on a predetermined curvature as indicated at 6 in a direction away from the returned portion 5, and affords a hook member adapted to be engaged over a finger when applying the member or clip. It is also to be observed that the returned portion 5 and the angularly disposed portion 6 are arranged in the same plane 85 as the intermediate portion of the strand. After the hook member 5 has been engaged with the rim 2 the strand is forced or bent inwardly over the rim 7 of the cover or closure member C and between adjacent slats 90 8 comprised in said cover or closure member. The hook 6 also serves, in view of its curved formation, to prevent damage to the fruit in close proximity to the clip or member M after the hook 6 has been bent over 95 the rim 7 which would not be the case if the portion 6 was straight.

From the foregoing description, it is thought to be obvious that a basket closure constructed in accordance with our invention 100 is particularly well adapted for use by reason of the convenience and facility with which it may be assembled and operated and it will be obvious that our invention is susceptible of some change and modification 105 without departing from the principles and spirit thereof and for this reason we do not wish to be understood as limiting ourselves to the precise arrangement and formation of the several parts herein shown in carrying out our invention in practice except as hereinafter claimed.

We claim:

In combination with a basket comprising staves, a rim connecting the free end portions of said staves, and a closure member, 5 a holding device formed of a single strand of bendable material and having one end portion returned to form an inwardly facing hook to straddle the lower marginal portion of the rim of the basket, the opposite end portion of the strand being extended, before applied and bent in a direction away from the returned portion and arranged in the same plane as the returned

portion longitudinally of the strand, said last named end portion being arranged on a 15 predetermined curvature to afford a finger engaging hook in applying the holding device and to protect the contents of the basket when said last named portion is bent inwardly of the rim of the closure.

ARTHUR JAMES THOMPSON.
HERMAN R. BUMKE.
